UNITED STATES PATENT OFFICE.

BERNARD D. WILLIS, OF CHICAGO, ILLINOIS, ASSIGNOR TO AUTOMATIC ELECTRIC COMPANY, OF CHICAGO, ILLINOIS, A CORPORATION OF ILLINOIS.

TELEPHONE-EXCHANGE TRUNKING SYSTEM.

1,342,242.

Specification of Letters Patent.

Patented June 1, 1920.

Application filed June 10, 1909, Serial No. 501,272. Renewed October 29, 1919. Serial No. 334,378.

To all whom it may concern:

Be it known that I, BERNARD D. WILLIS, a citizen of the United States of America, and resident of Chicago, Cook county, Illinois, have invented a certain new and useful Improvement in Telephone - Exchange Trunking Systems, of which the following is a specification.

My invention relates to telephone exchange systems of the character in which both manual and automatic switchboards are employed in extending calls between subscribers. For example, it is often desirable to provide suitable means whereby the subscribers of a small manual exchange, sometimes called a branch exchange, may not only communicate with each other, but whereby they may also call and be called by the subscribers of an automatic exchange. In such case, and should a subscriber of the manual exchange call a subscriber of the automatic exchange, the connection is necessarily accomplished through the medium of the manual switchboard at the branch exchange and the automatic switching apparatus at the main or automatic exchange. Also, in systems of this kind occasion often arises for precluding some of the subscribers at the branch exchange from communicating with the subscribers of the main exchange, and vice versa. For example, it is sometimes desirable that one or more of the telephones at the branch exchange be rendered incapable of connection with any of the subscribers' lines at the main or automatic exchange, but without interfering with the service between any and all of the subscribers at the branch exchange.

The object of my invention is, therefore, to provide a trunking operator's cord circuit of such character that it can be used in trunking to or from some of the subscribers' lines of the branch exchange, and having provisions whereby it cannot be used in connection with one or more of the subscribers' lines of the branch exchange, thus precluding all possibility of one or more of the subscribers of the branch exchange being given trunking connection to or from any of the subscribers of the main or automatic exchange, but without interfering with the establishment of calling connections between any and all of the subscribers of the said branch exchange. Another object is to provide an arrangement whereby the branch

exchange is signaled by the transmission of ordinary ringing current over the trunk line leading thereto. Another object is to provide an arrangement whereby any automatic connection that has been extended to a called automatic subscriber by the operator at the branch exchange will not be released should the said operator restore the calling key to normal while the calling subscriber's telephone is hung up or in normal condition.

It is also an object to provide certain details and features of improvement and combinations tending to increase the general efficiency of a semi-automatic telephone exchange system of this particular character.

To the foregoing and other useful ends my invention consists in matters hereinafter set forth and claimed.

In the accompanying drawings Figure 1 is a diagram of a combined manual and automatic private branch exchange telephone system embodying the principles of my invention, showing an automatic substation A and two manual substations A¹ and A².

Fig. 2 represents diagrammatically that part of the central office equipment consisting of the line switch F, master switch H, and the first and second selector switches K and L, respectively.

Fig. 3 represents a connector switch M in which the trunk lines from the second selector (Fig. 2) terminate, and a two-wire substation A³ connected with an individual line switch F' identical in type with the line switch F of Fig. 2.

The substations may be of any suitable or approved type. A represents an automatic substation so modified as to operate in connection with a two-wire system in which no ground connection is used at the subscriber's station. It comprises the usual receiver 2, switch-hook 3, induction coil 4 which consists of a primary winding 5 and secondary winding 6, transmitter 7, condenser 8, ringer 9 and impulse wheel 10, which latter has the usual impulse teeth 11. The impulse wheel 10 is secured to the shaft 12, to which shaft there is also secured a dial (not shown). When the dial is pulled down the springs 14 and 15 are not operated, but when the impulse wheel goes back the impulse teeth 11 are adapted to engage the cam 13 upon the end of the spring 14, and thereby carry the latter out of engagement with the spring 15. Upon the switch hook 3 is secured the

cam 16 which, when the switch hook is up, permits the springs 17 and 18 to engage, thereby bridging across the subscriber's line conductors 19 and 20 the primary circuit including the transmitter 7 in series with the primary winding 5. When the switch hook is lowered the spring 17 is carried out of engagement with the spring 18 and into engagement with the spring 21, whereby the ringer 9, in series with the condenser 8, is bridged across the line conductors 19 and 20 instead. The manual substation A' comprises the usual receiver 22 and switch hook 23 which, when the receiver is removed, is adapted to engage a contact point 24, thereby bridging the transmitter 25 in series with the primary winding 22 across the line. When the receiver is restored to the switch hook the primary circuit through the transmitter and primary winding is broken, and the ringer 26 in series with the condenser 27 is bridged across the line. The line switch F and master switch H (Fig. 2) are of the general type disclosed in British Patent No. 26,301 of 1906, and in the *Western Electrician* of Chicago, Illinois, of January 11, 18 and 25, 1908. As herein represented, the line switch F comprises a plunger (not shown) which is attached to the end of a plunger arm, and is adapted when released by the energization of the trip magnet 30 to enter a group of contact springs, forcing the springs 42, 48, 46 and 44 into engagement with the springs 43, 49, 47 and 45, respectively. These springs form the terminal of a trunk line leading to a selector switch K. Each of the line switches F is provided with a number of such groups of springs, each group forming the terminal of a trunk line leading to a separate selector switch. Each trunk line is multiplied through the corresponding springs in a number of line switches F. All of the line switches which have access to the same group of trunk lines are controlled by a common mechanism or master switch H in such a manner that the plungers of all the line switches of the group, when not actually in use, are maintained opposite an idle trunk line. After a line switch plunger has been operated it may be returned to normal position by a spring after the release magnet 31 has been energized and de-energized. The cut-off relay 55 is provided for disconnecting the trip magnet 30 from the line after the switch has been operated, and also when the line to which the switch belongs is called. The master switch H comprises essentially a motor magnet 60 for operating the ratchet wheel 61, which in turn holds the so-called plunger shaft 50 through the medium of the arm 62. The plungers of the idle line switches normally rest in locking engagement with the plunger shaft 50, through the medium of which they are maintained oppo-

site idle trunk lines. The master switch is also provided with a bank of contacts O, which bank comprises a common segment 64 and one individual segment α for each trunk line to which the line switches have access. The wiper 65 is adapted to always keep the common segment 64 in electrical connection with the individual segment corresponding to the trunk line in front of which their idle plungers are being held. The double-wound relay 63 is provided for the purpose of controlling the motor magnet 60.

The first selector K is a form of the selector switch disclosed in United States Letters Patent No. 815,321, granted March 13, 1906, to Keith, Erickson and Erickson, except that the form of release has been changed to that disclosed in United States Letters Patent No. 815,176, also granted March 13, 1906, to Keith, Erickson and Erickson. The release is such that as soon as the release magnet energizes, the switch shaft and side switch are restored. Instead of having two line relays, as is ordinarily the case, this selector is provided with one double-wound line relay 91. In addition, the said selector comprises a slow-acting relay 92 known as the private magnet relay, and another slow-acting relay 93 known as the releasing relay. The vertical magnet 94, the rotary magnet 95, the release magnet 96 and the private magnet 97 are well known and in general operate the same as the magnets of the selector patent. The said private magnet, of course, controls the side switch wipers 98, 99, 100 and 101. These relays may be made slow acting in any manner known to the art, for example, by providing each relay with an additional low resistance winding closed upon itself, or by providing each relay with a copper shield, which copper shield is indicated in the drawings by the small squares at the top of the coil. The second selector L is substantially the same as the first selector K and is equipped with the same number of magnets, namely the line relay 102, the private magnet relay 103, the releasing relay 104, the release magnet 105, the vertical magnet 106, the rotary magnet 107 and the private magnet 108. The circuits, however, are somewhat different and this difference will be taken up later.

The connector switch M is a modified form of the connector switch disclosed in Patent No. 815,176 hereinbefore referred to. The connector switch shaft (not shown), like the switch shaft of the selector, carries the line wipers 109 and 110 α and the private wiper 111. The connector switch is also controlled by the calling subscriber through the medium of the double-wound relay 112. The line relay 112 is provided with the windings 113 and 114. One terminal of the winding 113 is connected to the battery lead, 130

- while the other terminal is connected with the vertical trunk line conductor. The winding 114 is connected with ground and also with the rotary trunk line conductor.
- 5 This line relay 112 directly controls the vertical magnet 115. The connector switch is provided with the usual rotary magnet 116, and with the slow-acting release relay 117 which is the same as the release relay 104 of the second selector switch. As usual, the private magnet relay 118 controls the private magnet 119, which latter controls the side switch wipers 120, 121, 122, 123 and 124. The back-bridge relay 125, comprising the windings 126 and 127, provides the means whereby the called subscriber is furnished with battery current for talking purposes. As here shown, the connector switch is of the automatic ringing type—that is, a 20 signaling of the called subscriber is not dependent upon the calling subscriber pressing a signaling button when he calls a line not his own; for as soon as connection is established with the desired line the interrupter 128 intermittently closes an energizing circuit through the ringer relay 129, whereby the terminals of the ringer generator I are intermittently bridged across the normal conductors of the called line.
- 25 The relay 130 is so arranged that if a busy line is called, the connector side switch is locked in second position, and the calling subscriber is given the busy signal. The means whereby the connector switch may be 30 restored to normal position is provided by the usual release magnet 131 which, when the connector switch shaft is raised one or more steps, is connected to the battery lead by the contact point 132 and the normal spring 133. By means of the condensers 134 and 135 the circuit of the connector switch is divided into two sections. The busy signaling apparatus J comprises the interrupter 136 in series with the winding 137 of the 45 induction coil 138. The winding 139 is connected with the spring 140, and when the relay 130 energizes, the busy signaling apparatus is connected with the side switch wiper 120.
- 50 The manual stations A' and A² are each connected with lines which terminate in the jacks C' and C², respectively, of the private branch, and the automatic substation A is connected with a line which terminates in 55 the jack C. The cord circuit D, which is adapted to connect with the jacks C, C' and C², is used by the operator to connect a substation of the private branch exchange with an outgoing trunk line to the main central exchange, and is also used by the in-calling subscribers to the private branch exchange. The cord E is used to connect any two local substations—that is, any two substations 60 having their lines terminating in the private branch board, such as substations A' and A², for example. The cord circuit E is provided with the plugs c' and c² which are adapted to engage the jacks C' and C². The relays 157 and 158, in connection with the relays 159 and 160, provide means for 70 supplying the substations with battery current for talking purposes. By the use of the signal lamps 161 and 162 the operator obtains supervision over the lines corresponding to the jacks in which the plugs c² 75 and c' are inserted. The condensers 163 and 164 divide the talking circuit into two sections. By means of the key f the operator bridges her talking circuit across the calling end of the cord circuit, and by 80 means of the key f' a signaling current is sent over the called line.
- The cord circuit D is adapted for making calls both ways over the trunk conductors 165 and 166 which connect the main 85 and sub exchanges. The signaling lamp 167 indicates to the operator when the trunk line conductors 165 and 166 have been seized by a calling subscriber at the main automatic exchange, and the lamp 168 acts 90 as a supervisory signal. By means of the key e the operator may connect the line terminals of her calling device to the plug c, or may bridge the generator across the said plug. In this way the subscriber of the 95 private branch exchange may be called or connected with the trunk conductors 165 and 166. Under certain conditions the relay 169 controls the supervisory lamp 168 and the line signal lamp 167. 100
- The operation of the cord circuit E may be better understood by considering its use for connecting one substation with another. Suppose, for example, that the subscriber at substation A' desires to communicate 105 with the subscriber at substation A². When the calling subscriber removes the receiver 22 the switch hook 23 engages the contact point 24, thereby establishing an energizing circuit through the line relay 160. Said 110 circuit extends from ground G⁴ through the springs 170 and 171, conductor 172, switch hook 23, contact point 24, primary winding 22^a, transmitter 25, conductor 173, relay 160 to the battery lead 174, thence through battery B³ to ground G³. The relay 160, upon energizing, draws its armature 175 into contact with the contact point 176, thus closing the circuit through the line lamp 177. The circuit through said lamp extends from ground G⁵ through the lamp 177, springs 178 and 179, armature 175, contact point 176 to the battery lead 174, thence through battery B³ to ground G³. In response to the signal the operator inserts the 120 plug c' into the jack C', thereby causing the tip 180 and the sleeve 181 of the plug c' to engage the tip and sleeve springs 171 and 182 and carry them out of engagement with the contact points 170 and 183, respectively. 125
- 130

One energizing circuit through the relay 160 is thereby broken and another circuit established extending from ground G^2 through the relay 158, tip 180 of the plug c' , jack spring 171, over conductor 172, through substation A' , returning over conductor 173 to the relay 160, through said relay to the battery lead 174, thence through battery B^3 to ground G^3 . Upon bridging 10 her set across the line by means of the key f the operator learns that the substation A^2 is desired. She then inserts the plug c^2 into the jack C^2 , thereby causing the tip 184 and the sleeve 185 of the plug c^2 to engage 15 the tip and sleeve springs 186 and 187, respectively. She then throws the key f' , thereby sending signaling current through the ringer at substation A^2 .

Upon removing the receiver from the 20 switch hook the subscriber at substation A^2 closes the circuit which provides the transmitter with battery current for talking purposes. This circuit extends from ground G^6 through the relay 157, conductor 188, tip 25 184, jack spring 186, conductor 189, through substation A^2 , conductor 190, through the ring spring 187, plug sleeve 185, jack sleeve 191, conductor 192, relay 159 to the battery lead 174, thence through battery B^3 to 30 ground G^3 . The substation A' is provided with battery current for talking purposes over the circuit which is closed through the relays 158 and 160 when the plug c' is inserted in the jack C' , which circuit has 35 already been traced. Furthermore, at the time when the plug c' is inserted in the jack C' a circuit is closed through the relays 194 and 160. This circuit extends from ground G^7 through relay 194, conductor 195, sleeve 40 181, jack spring 182, through the relay 160 to battery lead 174, thence through battery B^3 to ground G^3 . The relay 194, on energizing, closes a circuit through the supervisory lamp 161. This circuit extends from ground G^6 45 through the armature 196, contact point 197, through the supervisory lamp 161, contact point 198, armature 199 to the battery lead 174, thence through battery B^3 to ground G^3 .

As soon as the called subscriber at station 50 A^2 answers, the energizing circuit through the relay 157 pulls up the armature 196, thus breaking a circuit through the supervisory lamp 161, thereby indicating to the operator that the call has been answered.

55 When the subscriber at substation A^2 hangs up his receiver the circuit through the relay 157 is broken, allowing the armature 196 to fall back and again close the circuit through the lamp 161.

60 When the subscriber at substation A' hangs up his receiver the circuit through the relay 158 is broken, and the armature 200 falls back into contact with the contact point 201, thereby closing the circuit through the lamp 162. The operator, seeing both lamps

lighted, knows that the conversation has been completed and proceeds to withdraw the plugs c' and c^2 .

Suppose that the subscriber at substation A' desires connection with the substation A . 70 In that case the plug c^2 will be inserted in the jack C and the subscriber at substation A called in the regular manner. When the receiver 2 is then removed from the switch hook 3 a circuit is closed through the relays 75 157 and 202, and the two substations A and A' are connected in a manner similar to that previously explained. Of course, should the subscriber at substation A desire connection with the subscriber at substation A' 80 be removed his receiver from the hook, closing the springs 17 and 18, and thereby completing an energizing circuit through the signal relay 202. In this case the plug c' will be inserted in the jack C and the plug 85 c^2 into the jack C' . In a similar manner subscriber A^2 can call subscriber A , or subscriber A can call subscriber A^2 .

Suppose that the subscriber at substation A^2 desires to call the subscriber at substation A^3 , which is a substation at the central exchange. Upon learning that the substation A^3 , the calling number of which, for example, may be taken as 2220, is wanted, the operator removes the plug c' from the 90 jack C^2 and substitutes the plug c of the trunk circuit D. She then throws the key e' , thus bridging her calling device N across the line. As soon as this is done a circuit is closed through the said calling 100 device, said circuit extending from ground G^9 at F (Fig. 2), through the trip magnet 30, bridge-cut-off springs 57 and 56, conductor 203, rotary line conductor 166, through the springs 204 and 205, conductor 105 203, the operator's calling device N , conductor 207, springs 208 and 209, conductor 210, springs 211 and 212, vertical line conductor 165, through the bridge-cut-off springs 58 and 59, resistance 161^a to the 110 battery lead 110, thence through battery B to ground G . The trip magnet 30, upon energizing, attracts its armature 34, causing the plunger 28 to be driven into the bank jack Q. As soon as the plunger 28 115 enters the said bank jack it operates to press the bank springs 47 and 46, 49 and 48, 43 and 42, and 45 and 44 into contact. The closing of the springs 46 and 47 completes an energizing circuit through the bridge- 120 cut-off relay 55. This circuit extends from ground G^{10} through the springs 46 and 47, conductor 167^a, through the relay 55 to the battery lead 110, thence through battery B and to ground G . The cut-off relay then 125 operates the cut-off relay springs, breaking the originally established circuit through the trip magnet 30. The closing of contact between the bank springs 42 and 43 extends the subscriber's vertical line conductor 165 130

into contact with the trunk conductor 82, and the making of contact between the bank springs 44 and 45 presses the rotary line conductor 166 into contact with the trunk conductor 83. As a result an energizing circuit is established through the line relay 91 of the first selector K. This energizing circuit extends from ground G^{11} through the winding 215 of the relay 91, contact point 216, side switch wiper 99, trunk conductor 83, bank springs 45 and 44, conductor 166, thence through the calling device N to the vertical line conductor 165, through the bank springs 42 and 43 to the trunk conductor 82, thence through the side switch wiper 98, contact point 217, winding 218 of the line relay 91 to the battery lead 110, thence through battery B to ground G. The closing of this circuit causes the line relay 91 to energize, the windings 215 and 218 being in series, and operates to separate the springs 219 and 220, placing the spring 220 into contact with the spring 221. In consequence the slow-acting release relay 93 is energized and in turn operates to shift the spring 222, which is connected with the spring 223, out of engagement with said spring and into engagement with the spring 224. The energizing circuit for the relay 93 extends from ground G^{12} to springs 220 and 221, through relay 93 to the battery lead 110, thence through battery B to ground G. By slow-acting relay is meant relays that are slow only in deenergizing. By the energization of the relay 93, as described, it will be seen that the spring 219 is placed in contact with the slow-acting private magnet relay 92, and through said relay to the vertical magnet 94, making it possible to send ground impulses from the spring 220 through said magnet 92 to the vertical magnet 94 while the relay 93 is energized.

The foregoing is accomplished by the operator when she bridges her calling device across the line. She continues the call by breaking said circuit in any suitable manner a number of times, corresponding to the units in the first digit. It will be assumed that her calling device is equipped with the regular dial. When, therefore, the dial is drawn down for the said first digit 2, on returning to its normal position it operates to twice break the established circuit just described. Each time that this circuit is broken the line relay 91 of the selector K falls back and permits the spring 220 to come into contact with the spring 219, and impulses are transmitted from ground G^{12} at K (Fig. 2) by way of the springs 220 and 219 of the line relay and the springs 222 and 224 of the slow-acting release relay 93 through the private magnet relay 92, the vertical magnet 94, side switch contact point 225, wiper 101 to the battery lead 110, thence through battery B to ground G. It is, of course, understood that the impulses are so regulated that the slow-acting relay 93 does not have time to deenergize between impulses. The first impulses transmitted by the line relay 91 over the circuit described causes the private magnet relay 92 to energize, and said relay remains so during the succeeding impulses owing to its slow-acting character. Upon energizing, the said relay 92 presses the springs 226 and 227 into contact, thereby energizing the private magnet 97 by a current from ground G^{12} through said springs 226 and 227, through magnet 97 to battery lead 110, thence through battery B to ground G. The said private magnet 97 remains energized as long as the slow-acting relay 92 is energized. The impulses produced by the line relay 91 also energize the vertical magnet 94, which magnet then operates to raise the switch shaft one step for each impulse. Since two impulses are transmitted to the shaft the line and private wipers 88, 89 and 90 are raised two steps and brought opposite the first contacts of the second bank level of the selector K. As soon as the operator's dial assumes its normal position the line relay 91 again resumes its constant energized condition, so that the private magnet relay 92 deenergizes, whereby the springs 226 and 227 are allowed to separate and the private magnet 97 as a result allowed to deenergize, which then allows the side switch to shift to second position. As soon as the side switch shifts to second position the side switch wiper 101 engages the contact point 228, thereby establishing an energizing circuit through the rotary magnet 95, said circuit extending from ground G^{11} through the interrupter springs 229, through the rotary magnet 95 to the contact point 228, thence through the side switch wiper 101 to the battery lead 110, and through battery B to ground G. The rotary magnet then attracts its armature, rotating the shaft one step and thus causing the line wipers to come into contact with the first trunk line in the second level. When the rotary magnet 95 attracts its armature the armature of the private magnet 97 is operated at the same time by the usual private armature finger carried by the rotary armature. The result is that the first operation of the rotary magnet not only rotates the shaft wipers into engagement with the first trunk line, but as the rotary armature falls back the private armature is also permitted to fall back, at which time the side switch shifts to third position. This is only true if the first trunk is idle, which trunk, it is assumed, terminates in a second selector L. It will be seen that when the side switch passes to third position the side switch wiper 100 engages the contact point 230, whereby the private wiper 90 is 130

placed in connection with ground G^{12} since the line relay 91 is energized. The circuit over which this connection is maintained is as follows: from ground G^{12} through the 5 line relay springs 220 and 221, conductor 231 to the contact point 230, thence to the side switch wiper 100 and over the conductor 232 to the private wiper 90. The private wiper 90 being in engagement with one of the 10 multiple private bank contacts corresponding to the trunk line terminating in the selector L, all of the multiple private bank contacts connected thereto are thus provided with a guarding potential for preventing 15 other selectors from seizing the same trunk line. If the first trunk line is busy, however, the armature of the private magnet does not fall back with the rotary armature at the end of the first step, but is retained 20 by the private magnet, which is then energized over a circuit which is closed as soon as the private wiper engages the first contact, which will, of course, be grounded. When this happens an energizing circuit is 25 set up through the private magnet 97 extending from this grounded private bank contact to the wiper 90, over the conductor 232 to the side switch wiper 100, thence to the contact point 233, through the private 30 magnet 97 to the battery lead 110, thence through battery B to ground G. It will be seen, therefore, that the private magnet 90 will retain the side switch locked in second 35 position as long as the private wiper 90 encounters busy trunk lines. However, as soon as the rotary magnet 95 advances the wipers onto an idle trunk line, the energizing circuit for the private magnet 97, including the private wiper 90, is broken, and 40 as a result the private magnet 97 will de-energize at the last stroke of the rotary magnet, permitting the side switch to pass to third position. A guarding potential is then established at the private wiper 90, 45 and then over the private bank multiple contacts, as already explained.

It will be assumed that the first selector K stops on the first trunk line, as previously explained. Then when the side switch 50 passes to third position the side switch wipers 98 and 99, upon engaging the third-position contacts 234 and 235, respectively, extend the trunk conductors 82 and 83 to the trunk conductors 245 and 244 which 55 terminate in the second selector L. It is evident that when the side switch of the first selector is in first position the wipers 98, 99, 100 and 101 are in engagement with the contact points 217, 216, 238 and 225, respectively; when in second position the wipers are in engagement with the contact points 239, 240, 233 and 228; and in third position the wipers are in engagement with the contact points 234, 235, 230 and 241. It will 65 be seen that when the side switch thus passes

to third position the energizing circuit for the line relay 91 of the selector K is cut off from the said relay, which restores to normal. The energizing circuit for the line relay 91 cannot be broken until the said side 70 switch passes to third position, because the side switch contact points 217 and 239 are connected on one side, and the side switch contact points 216 and 240 are likewise connected on the other side. When the connection with the ground G^{12} is interrupted at a point between the line relay springs 220 and 221 a guarding potential is established 75 at the private bank contact engaged by the private wiper 90 from the selector L as follows: As soon as the side switch trips to third position the line relay 102, like the line relay 91, energizes over the following circuit: from ground G^{12} through the winding 242 of the relay 102, side switch wiper 243 of the second selector L, thence through the trunk conductor 244, rotary line wiper 89 of the first selector K, contact point 235, side switch wiper 99, through the calling device N, back over the other side of the 80 line to the first selector side switch 98, contact point 234, vertical line wiper 88 to the side switch wiper 246 of the second selector L, thence through the winding 247 of the line relay 102 to the battery lead 110, thence 85 through battery B to ground G. The line relay 102 being similar to the line relay 91, the spring 248 is separated from the spring 249 and carried into contact with the spring 250. As a result the slow-acting release relay 104 is energized by a flow of current 90 from ground G^{14} through the spring 248 and 250, release relay 104 to the battery lead 110, thence through battery B to ground G. The slow-acting relay 104, upon energizing, 95 shifts the spring 251 from the spring 252 and into contact with the spring 253, and the two additional springs 254 and 255 are pressed into contact at the same time, whereby the ground connection G^{15} is substituted 100 at the private wiper 90 for ground G^{12} . This is evident, since the side switch of the selector L is in first position, and is also true when the side switch is in second position, as indicated by the side switch contact 105 points 257 and 256 being connected. Connection having been established with the second selector L, the operator pulls the dial in accordance with the second digit 110 2, with the result that the line relay 102 is operated twice and the spring 248 carried twice into engagement with the spring 249, while the slow-acting relay 104 is energized. The result is that at the first impulse the slow-acting private magnet relay 103 is energized, and the vertical magnet 106 operated once. The slow-acting relay 103, of course, remains energized until the second impulse is sent, which again operates the vertical magnet 106 through the slow-acting 115 120 125 130

relay 103. In this way the switch shaft of the second selector L is raised two steps by the vertical magnet 106, and the line and private wipers 258, 259 and 260 are placed opposite the first contact of the second level of the second selector bank. It will be evident that as soon as the slow-acting relay 103 energizes, the springs 261 and 262 are pressed into contact and an energizing circuit is established for the private magnet 108 from ground G¹⁴ through the springs 261 and 262, through the private magnet 108 to the battery lead 110, thence through battery B to ground G. The private magnet attracts its armature, but does not release the side switch to second position until all of the impulses have been sent in, after which the slow-acting relay 103 deenergizes, as in the first selector K, which then interrupts the circuit between the springs 261 and 262. The energizing circuit for the vertical magnet 106 and for the slow-acting relay 103 extends from ground G¹⁴ through the line relay springs 248 and 249, through the relay springs 251 and 253 to the private magnet relay 103, thence to the vertical magnet 106, side switch point 263, side switch wiper 264 to the battery lead 110, thence through battery B to ground G. When the side switch passes to second position the side switch wiper 264 engages the contact point 265, thus closing the energizing circuit for the rotary magnet 107 from ground G¹³ to the interrupter springs 266, rotary magnet 107, side switch contact point 265, side switch wiper 264 to the battery lead 110, thence through battery B to ground G. It will be seen that in the selector L, as in the selector K, at the first impulse through the rotary magnet 107 the armature of the private magnet 108 is operated to trip the side switch to third position, provided the first trunk line is idle, by which operation the subscriber's line is placed in connection with the connector switch M. However, if the first trunk line is not idle, the private wiper 260 will be carried onto grounded contacts, as described in connection with the first selector K, with the result that the private magnet 108 is energized and maintained energized, locking the side switch in second position until the rotary magnet has advanced the shaft and wipers beyond the last busy trunk, at which time the private magnet deenergizes and permits the side switch to pass to third position in the usual manner. The shaft wipers 258, 259 and 260 having been rotated into engagement with the trunk conductors 268, 269 and 270, and the side switch wipers 246 and 243 having passed to third position, the circuit is thereby extended to the connector switch M. The connector line relay 112 instantly energizes, the current flowing from ground G¹⁶ through the winding 114 of the line relay 112 to the trunk conductor 269, rotary line wiper 259 of the second selector L, contact point 273^a, side switch wiper 243 to the rotary side of the line, through the first selector K, line switch F, calling device N to the vertical side of the line, back through the line switch F, first selector K and the second selector L to the side switch wiper 246, contact point 272, line wiper 258, vertical trunk conductor 268, winding 113 of the line relay 112 to the battery lead 110, thence through battery B to ground G. The line relay 112, upon energizing, operates to shift the spring 273 from the spring 274 to the spring 275, whereby an energizing circuit is established through the release relay 117, said circuit extending from ground G¹⁷ through the springs 273 and 275, relay 117 to the battery lead 110, thence through battery B to ground G. When the relay 117 energizes, the spring 276 is shifted out of contact with the spring 277 and into contact with the spring 278, and the spring 279 is shifted into engagement with the spring 280. This primary operation of the connector relays 112 and 117 occurs at the instant that the side switch wipers 246 and 243 of the selector L pass to third position, and extends the subscriber's line conductors to the connector M. The engagement of the springs 280 and 279 establishes a guarding potential for protecting the trunk line conductors 268, 269 and 270 against seizure by another line or second selector. This potential extends from ground G¹⁸ to the side switch wiper 123, springs 279 and 280, conductor 270 to the private bank contact engaged by the shaft wiper 260. Furthermore, when the side switch of the second selector L passes to third position a new energizing circuit is established through the release relay 104, said circuit extending from ground G¹⁸ at the connector switch through the side switch wiper 123 and springs 279 and 280 to the conductor 270, through the shaft wiper 260, side switch wiper 271, conductor 281, through the release relay 104 to the battery lead 110, thence through battery B to ground G. Also, this same guarding potential established at the contact engaged by the private shaft wiper 260 is extended to the private bank contact engaged by the shaft wiper 90 of the first selector K. When the side switch of the second selector L passes to third position the path over which this potential extends is the same as just traced to the side switch wiper 271, from whence it goes to the shaft wiper 90. The operation of the dial for the last two digits affects the connector switch, and when the dial is operated for the third digit 2 the circuit through the line relay is twice broken, thereby momentarily deenergizing said relay twice, whereby the spring 273

twice engages the spring 274, thus sending two impulses to the vertical magnet 115 from ground G^{17} through the springs 273 and 274, springs 276 and 278, through the 5 vertical magnet 115, contact point 282, side switch wiper 124, private magnet relay 118 to the battery lead 110, thence through battery B to ground G. The private magnet relay 118 energizes when the first impulse 10 is delivered, and since the said relay is slow-acting it remains in an operated position until all of the vertical impulses are sent. The vertical magnet, upon being energized 15 twice, operates to carry the shaft wipers 109, 110 and 111 two steps to a point opposite the second level. The relay 118, upon energizing, shifts the spring 283 out of engagement with the spring 284 and into engagement with the spring 285. Also, the 20 spring 286 is shifted out of engagement with the spring 285. When the springs 283 and 285 engage, an energizing circuit is established through the private magnet 119 from ground G^{19} through the springs 285 25 and 283, private magnet 119 to the battery lead 110, thence through battery B to ground G.

The relay 118, being a slow-acting relay, remains in an operated position while the 30 vertical impulses are being sent; but after all of the impulses are delivered, and the line relay 112 returns to its operated position, the circuit through the relay 118 becomes broken, thus permitting the springs 35 286 and 283 to return to normal position. When the springs 283 and 285 disengage, the circuit through the private magnet 119 breaks, whereby the said magnet deenergizes, permitting the side switch to pass 40 from first to second position. The operator now pulls the dial for the last digit 0, thereby transmitting ten impulses, and operating the line relay 112 ten times. Each time that the line relay springs 273 and 274 engage, an 45 energizing circuit is established through the rotary magnet 116 from ground G^{17} through the said springs 273 and 274, through the springs 276 and 278, locking relay springs 287 and 288, through the rotary magnet 50 116 to the contact point 289, thence through the side switch wiper 124, through the private magnet 118 to the battery lead 110, thence through battery B to ground G. Again the private magnet relay energizes, 55 as in the previous case, remaining so until all of the impulses are transmitted, thereby retaining the private magnet energized. The rotary magnet 116 thus operates to rotate the shaft wipers into engagement with 60 the desired line #2220. As soon as the line relay 112 ceases to operate for the last digit, the private magnet relay 118 deenergizes, as hereinbefore explained, in this instance permitting the side switch to trip to third position. The result is that the side switch

wipers 120, 121, 122, 123 and 124 engage the contact points 290, 291, 292, 293 and 294, respectively. When the side switch wiper 122 engages the contact point 292 a guarding potential is completed at the private 70 wiper 111 for protecting the seized line from outside interference while the connection is established. This guarding potential extends from ground G^{20} to the contact point 292, thence by way of the side switch wiper 75 122, locking relay springs 295 and 296 to the private wiper 111. Not only does this guarding potential protect other connectors from seizing the same line over multiples of the normal conductors 297, 298 and 299, but 80 it also provides means for energizing the cut-off relay 300 at the line switch F', whereby the switch F' is prevented from operating when the called subscriber removes his receiver 301 from the switch hook 302. While 85 the side switch is in first or second position a guarding potential is established for the trunk conductor 270 at ground G^{18} through the side switch wiper 123. The reason for this is that the guarding potential from the 90 ground G^{17} is interrupted while the line relay 112 is operating, and there is a possibility of some other selector similar to the second selector L stopping on the same trunk line. After the side switch passes to third 95 position, however, there is no such possibility, and the potential is provided by ground G^{17} through the line relay springs instead. When the side switch wipers 120 and 121 engage their third-position contact 100 points 290 and 291 the trunk conductors 165 and 166 are placed in connection with the called subscriber's line over the heavy conductors shown, passing through the ringer relay springs 303 and 304 on one side and 105 305 and 306 on the other. As soon as connection is thus established the ringer relay 129 is energized over the circuit established when the side switch wiper 124 engages the contact point 294, the energizing current 110 flowing from ground G^{21} through the interrupter 128, through the back-bridge relay springs 308 and 309, ringer relay 129, conductor 310, contact point 294, side switch wiper 124, private magnet relay 118 to the 115 battery lead 110, thence through battery B to ground G. It will be seen that as the interrupter 128 revolves, the energizing circuit of the ringer relay 129 will be broken periodically, so as not to ring the called subscriber continuously. Each time that the ringer relay is energized the springs 303 and 305 are separated from the ringer relay 120 springs 304 and 306, thereby separating the called line from the calling line and 125 pressing the springs 303 and 305 into contact with the springs 311 and 312, which latter are the terminals of the ringer generator I. As a result ringing current is sent over the called line for energizing the bell 313, 130

- while the springs 314 and 315 are in contact. As soon as the called subscriber answers, the back-bridge relay 125 is energized by a flow of current from ground G^{20} , contact 5 point 292, side switch wiper 122, winding 127 of the back-bridge relay 125, conductor 316, ringer relay springs 306 and 305, side switch wiper 121, contact point 291, rotary line wiper 110, rotary normal conductor 10 298, rotary line conductor 317, switch hook springs 315 and 318, impulse springs 319 and 320, transmitter 321, vertical line conductor 322, vertical normal conductor 297, vertical line wiper 109, contact point 290, 15 side switch wiper 120, ringer relay springs 303 and 304, conductor 323, winding 126 of the back-bridge relay 125, thence to the battery lead 110, and through battery B to ground G. When the back-bridge relay 125 20 is energized the energizing circuit for the ringer relay 129 is interrupted at a point between the springs 308 and 309, keeping the ringer relay deenergized as long as the called subscriber is on the line.
- 25 The operator, having obtained the called subscriber, restores the key e' , thereby connecting the substation A^2 directly with the trunk line conductors 165 and 166, since the sleeve contact 208^a of the plug C engages the sleeve 191 which is connected with the main battery B^3 through the relay 159. An energizing circuit therefore extends from ground G^s through the relay 169 over the sleeve contact 208^a, ring 191 to the relay 30 159, thence to battery lead 174, and through battery B^3 to ground G^s . When the relay 169 energizes and pulls the armature 209^a into contact with the contact point 210^a, the station A^2 is connected with the trunk conductors 165 and 166, as shown, over the heavy line conductors of the cord circuit D. The operator, throwing her listening key e' , informs the subscriber at substation A^2 that the connection has been completed.
- 40 The trunk conductors are extended through station A^2 over the following circuit: Starting with the conductor 165 the circuit extends through the springs 212 and 324, springs 325 and 326, through the tip of the plug C, jack spring 186, conductor 189, through the station A^2 , conductor 190, jack spring 187, sleeve of the plug e , through the springs 329 and 330, contact point 210^a, armature 209^a, through the winding 333 of the 45 relay 334 through the armature 335, contact point 336, conductor 337, through the springs 327 and 204 to the trunk conductor 166. When the relay 169 is energized the armatures 335 and 338 are brought into 50 contact with the contact points 336 and 339, respectively. This closes a circuit through the lamp 168 as long as the key e' is thrown after plugging in the plug e , said circuit extending from ground G^s through the armature 338, conductor 340, armature 341, 55 contact point 342, lamp 168 to the main battery B^2 , thence through battery B^2 to ground G^2 . As soon as the key e' is returned, and the connection completed, the circuit through the lamp 168 is broken at 60 the contact point 342 by the energization of the relay 334 through the winding 333, as before stated.
- 65 After the subscribers are through talking, if the calling subscriber hangs up his receiver he opens the line circuit at a point between the springs corresponding to the springs 23 and 24 at the substation A' , thereby deenergizing the relays of all of the switches as follows: At the instant that the 70 circuit is broken between the said springs 23 and 24 the double-wound line relay 112 and the release relay 117 of the connector M deenergize. At the moment that the slow-acting relay 117 and the line relay 112 75 deenergize, the energizing circuit for the release magnet 131 is closed at a point between the springs 276 and 277, and at another point between the springs 274 and 273. The flow of current is, therefore, sent 80 from ground G^{17} through the springs 274 and 273, through the springs 276 and 277, the release magnet 131, thence through said magnet to the off-normal spring 133, contact point 132 to the battery lead 110, thence 85 through battery B to ground G. The release magnet instantly releases the connector switch shaft and side switch, thereby breaking the energizing circuit through the back-bridge relay 125 if the called subscriber has not in the meantime restored his receiver, and also the energizing circuit 90 through the bridge-cut-off relay 300 of the called line switch F'. As soon as the connector switch shaft reaches its lowest position it breaks a circuit for the release magnet 131 by separating the off-normal spring 133 from the contact point 132, at which instant the release magnet of the connector is 95 also restored. The operation of the line relay 112 and of the slow-acting relay 117 not only causes the release of the connector, as described, but also the release of the succeeding circuits, because the ground connection from ground G^{17} to the trunk-release 100 conductor 270 is interrupted by both of these relays. Since the release relays 104 and 93 are dependent upon that ground for their energized condition, it follows that 105 they will fall back, with the following result: As soon as the release relay 104 of the second selector L deenergizes, the spring 251 falls back into normal engagement with the spring 252, thereby closing an energizing circuit for the release magnet 105 from 110 ground G^{14} through the springs 248 and 249, through the springs 251 and 252, the release magnet 105, thence to the contact point 343, off-normal spring 344 to the battery lead 110, thence through battery B to 115 120 125 130

ground G. As soon as the release magnet 105 energizes, the second selector side switch and switch shaft are restored, which latter, upon reaching its lowest position, opens up 5 a release circuit at a point between the off-normal spring 344 and the contact point 343, whereby the release magnet 105 is also restored. When the release relay 93 of the selector K deenergizes, the springs 222 and 10 223 are brought into contact and as a result the energizing circuit for the release magnet 96 is closed. The energizing current for this release magnet 96 flows from ground G¹² to the springs 220 and 219, 15 through said springs 223 and 222 to the release magnet 96, thence through said magnet to the contact point 345, off-normal spring 346 to the battery lead 110, thence through battery B to ground G. The release 20 magnet, upon energizing, then restores the first selector side switch and switch shaft, which latter, upon falling into position, opens an energizing circuit for the release magnet 96 at a point between the off-normal 25 spring 346 and the contact point 345. When the magnet 96 energizes a circuit is closed through the release magnet 31 of the line switch F, said circuit extending from ground G²² through the springs 347 and 30 348, conductor 84, bank contacts 49 and 48, release magnet 31 to the battery lead 110, thence through battery B to ground G. When the circuit through the relay 96 is broken by the separation of the off-normal 35 springs 345 and 346 the springs 347 and 348 separate, breaking the energizing circuit through the release magnet 31, thus allowing the armature to fall back and withdraw the plunger from the bank. The 40 system is then restored to normal and made ready for another call.

Should the subscriber at substation A desire to call the main exchange, the operator inserts the plug c into the jack C, thereby connecting him through the trunk D in the same manner that station A² was connected. A being an automatic substation the subscriber then proceeds to complete the call by operating his own dial. Upon 50 releasing in this instance, as in the preceding, the circuit through the relay 334 is broken, allowing the armature 341 to return into contact with the contact point 342, and thus closing the circuit through the lamp 168 from ground G⁸ through the relay armature 338, conductor 340, armature 341, contact point 342, lamp 168 to main battery. The glowing of this lamp then indicates to the operator that the trunk D has 55 been vacated. When the trunk D is seized by a subscriber from a main exchange the operator at the private branch exchange is signaled by the subscriber throwing generator on the line. When this is done a current is sent over the line 165 through the

springs 212 and 324, conductor 349, contact point 350, armature 335, conductor 351, winding 333 of the relay 334, armature 209^a through the condenser 352, and back over the trunk line 166 to the other side of the 70 generator. The relay 334 energizes, pulls up the armature 341 and establishes an energizing circuit through the windings 353 of the relay 334, and also to the lamp 167, over the following path: from ground G²² to the 75 contact point 354, through armature 341, conductor 340, armature 338, contact point 355, conductor 356, springs 357 and 358, conductor 359, and from thence through the winding 353 of the relay 334 on one hand, 80 and the lamp 167 on the other, to the battery B², thence through battery B² to ground G². The relay 334 consequently locks and maintains the circuit through the lamp 167, which calls the operator's attention. The 85 operator, throwing her listening key e', learns what substation of the private branch exchange is desired, and inserting the plug c into the jack of the desired line throws the generator key e, which sends out generator current to the station called.

In calling out over the trunk D the operator, in throwing the key e', bridges the resistance 360 across the line in the following manner, in order to maintain the connector 95 up in case the receiver at the calling station should be on the hook when the key e' is restored. When the key e' is thrown a circuit is closed extending from ground G⁸ to contact point 339, armature 338, conductor 340, 100 armature 341, contact point 342 to the springs 361 and 362, relay 363 to the battery lead B², thence through battery B² to ground G². This relay attracts the armature 364 and completes a locking circuit through 105 itself from ground G⁸, contact point 339, armature 338, conductor 340 to armature 341, contact point 342, armature 364, contact point 365, through relay 363 to battery lead B², thence through battery B² to ground G². At the same time that the armature 364 is attracted the armature 366 is likewise attracted against the point 367. This 110 bridges the resistance 360 between the springs 324 and 327. If the receiver is on 115 the hook at the calling substation when the operator throws back the key e', the resistance 360 will be bridged across the trunk conductors 165 and 166 by the engagement of the springs 324 and 327 with the springs 120 312 and 204, respectively. As soon, however, as the receiver at the calling substation is removed from the hook the energizing circuit of the winding 333 of the relay 334 is completed, as previously stated, 125 whereupon the locking circuit of the relay 363 is opened at a point between the armature 341 and contact 342. The relay 363 then deenergizes and opens the bridge through the resistance 360.

If, however, a subscriber at substation A' attempts to call the main exchange, it will be found impossible to make the connection. The operator, on learning that a trunk to the main exchange is desired, may insert the plug *c* into the jack C'. When this is done a circuit will not be established through the relay 169 as in the other instance, since the sleeve conductor 208^a is not connected with main battery through the sleeve 368; and since the line cannot be connected with the trunk D unless the armature 209^a makes contact with the contact point 210^a, it will be seen by referring to substation A' that they cannot call a substation of the main exchange.

From the foregoing it will be seen that I provide a trunking operator's cord circuit which is rendered operative by the insertion of the plug in the jack of one or more of the lines at the branch exchange, but which is rendered or retained in an inoperative condition when an attempt is made to use the same for connection with one or more other lines of the same exchange. Thus, some of the subscribers can call and be called by the subscribers of the main exchange, whereas other subscribers of the branch exchange have their service limited entirely to inter-communication between the subscribers of the branch exchange, inasmuch as they are entirely cut off from service to or from the main exchange. This would be desirable, for example, in a system involving a branch exchange requiring a considerable number of substations for local communication, but only a part of which substations in the ordinary transaction of business have occasion to be connected with substations of the main exchange. With this system employees of an institution who ordinarily have no occasion to call outside subscribers may be given a telephone for local communication, but will be unable to monopolize the trunks to the main exchange for personal and unimportant matters. Moreover, it will be seen that when the operator at the branch exchange is called by a subscriber at the main exchange, the trunk line signal at the trunking operator's cord circuit responds to the regular ringing current which passes over the trunk line from the main exchange. Again, the trunking connection which has been automatically extended to the called subscriber's line at the main exchange is not released if the trunking operator restores the calling key when the calling subscriber's telephone is hung up in normal condition.

What I claim as my invention is:—

1. In a telephone system, a trunking operator's cord circuit terminating at one end in a plug and at the other end in an automatic switch, a subscriber's line provided with means for rendering said cord circuit operative for talking purposes when con-

nection is made thereto, and another subscriber's line provided with means for rendering said cord circuit inoperative for talking purposes when connection is made thereto. 70

2. In a telephone system, a trunking operator's cord circuit provided with a normally open talking strand, a relay controlling said normally open strand, a subscriber's line provided with means for energizing said relay to close the talking strand, and another subscriber's line provided with means for causing said relay to remain in normal condition. 75

3. In a telephone system, a branch exchange and a main exchange, a trunk extending between the two exchanges, a cord and plug at the branch exchange permanently connected to said trunk, a plurality of subscriber's lines each provided with a jack adapted to receive said plug, circuit means at the jack of one of said lines for rendering said cord circuit operative for talking purposes, and circuit means at the jack of another of said lines for rendering 90 said cord circuit inoperative for talking purposes. 80

4. In a telephone exchange system, a subscriber's line, a trunk line adapted to be connected thereto, automatic means for extending connection therefrom, including an operator's calling key and automatic switches adapted to be released by opening the line circuit, and circuit means whereby the automatic connection is not released should 95 the operator restore the calling key while calling subscriber's telephone is hung up or in normal condition.

5. In a telephone system, a calling line, a trunk line, means for establishing a connection therebetween, automatic means for extending connection therefrom, including an operator's calling key and automatic switches adapted to be released by opening the line circuit, and a suitable resistance 105 adapted to be bridged across the trunk line, whereby the automatic connection is not released should the operator restore the calling key while the calling subscriber's telephone is hung up or in normal condition. 110 115

6. In a telephone system, a trunking operator's cord circuit, a subscriber's line provided with means for rendering said cord circuit operative for talking purposes when connection is made thereto, another subscriber's line provided with means for rendering said cord circuit inoperative for talking purposes when connection is made thereto, and electrically controlled means for calling and releasing automatically 120 over circuits each of which includes a portion of one side of the talking circuit in series with a portion of the other side thereof. 125

7. In a telephone system, a trunking op- 130

erator's cord circuit provided with a normally open talking strand, a relay controlling said normally open strand, a subscriber's line provided with means for energizing said relay to close the talking strand, another subscriber's line provided with means for causing said relay to remain in normal condition, and electrically controlled means for calling and releasing automatically over circuits each of which includes a portion of one side of the talking circuit in series with a portion of the other side thereof.

8. In a telephone exchange system, a subscriber's line, a trunk line adapted to be connected thereto, automatic means for extending connection therefrom, including an operator's calling key, circuit means whereby the automatic connection is not released should the operator restore the calling key while the calling subscriber's telephone is hung up or in normal condition, and electrically controlled means for calling and releasing automatically over circuits each of which includes a portion of one side of the talking circuit in series with a portion of the other side thereof.

9. In a telephone system, a subscriber's line, a trunk line adapted to be connected thereto, automatic means for extending connection therefrom, including an operator's calling key, a suitable resistance whereby the automatic connection is not released should the operator restore the calling key while the calling subscriber's telephone is hung up or in normal condition, and electrically controlled means for calling and releasing automatically over circuits each of which includes a portion of one side of the talking circuit in series with a portion of the other side thereof.

10. In a telephone system, a trunking operator's cord circuit terminating at one end in a plug and at the other end in an automatic switch, a subscriber's line provided with means for rendering said cord circuit operative for talking purposes when connection is made thereto, another subscriber's line provided with means for rendering said cord circuit inoperative for talking purposes when connection is made thereto, and a common battery for supplying current for talking purposes.

11. In a telephone exchange system, a subscriber's line, a trunk line adapted to be connected thereto, automatic means for extending connection therefrom, including an operator's calling key, and automatic switches adapted to be released by opening the line circuit, circuit means whereby the automatic connection is not released should the operator restore the calling key while the calling subscriber's telephone is hung up or in normal condition, and a common battery for supplying current for talking purposes.

12. In a telephone system, a subscriber's line, a trunk line adapted to be connected therewith, automatic means for extending connection therefrom, including an operator's calling key and automatic switches adapted to be released by opening the line circuit, a suitable resistance adapted to be brought into suitable relationship with the trunk line, whereby the automatic connection is not released should the operator restore the calling key while the calling subscriber's telephone is hung up or in normal condition, and a common battery for supplying current for talking purposes. 75

13. In a telephone system, subscribers' lines, an operator's cord circuit adapted to be connected with said lines, a relay for said cord circuit, an operator's key adapted when operated to close an energizing circuit for said relay, a suitable resistance adapted to be bridged across the cord circuit by the operation of said relay, and locking means for said relay whereby said bridge is maintained closed after said key is released. 80

14. In a telephone system, subscribers' lines, a trunk, a trunking operator's cord circuit connected with said trunk and adapted for use in establishing a connection either to or from said trunk, a relay for said cord circuit, and a trunk signal and a supervisory signal both under the control of said relay. 90

15. In a telephone system, a group of lines, a trunk, another group of lines, circuit closing means for extending connection to said trunk from any one of said lines, said trunk being normally inoperative for extending a circuit thereover, whereby when connection is extended to said trunk from said first group of lines the connection cannot be extended beyond said trunk, electrically controlled means for rendering said trunk circuit operative, and auxiliary circuits associated with said second group of lines for controlling said electrically controlled means whereby when any connection is extended from any one of said lines of the second group to the said trunk the trunk becomes operative to extend a connection therefrom. 105

16. In a telephone system, a group of lines, a cord circuit, another group of lines, circuit closing means for extending connection to said cord circuit from any one of said lines, said cord circuit being normally inoperative for extending a circuit thereover, whereby when connection is extended to said cord circuit from said first group of lines the connection cannot be extended beyond said cord circuit, electrically controlled means 120 for rendering said cord circuit operative, auxiliary circuits associated with said second group of lines for controlling said electrically controlled means whereby when any connection is extended from any one of said 125 lines

lines of the second group to the said cord circuit the cord circuit becomes operative to extend a connection therefrom.

17. In a telephone system, a group of 5 lines, a trunk, another group of lines, circuit closing means for extending connection to said trunk from any one of said lines, said trunk being normally inoperative for extending a circuit thereover, whereby when 10 connection is extended to said trunk from said first group of lines the connection cannot be extended beyond said trunk, electrically controlled means for rendering said trunk circuit operative, auxiliary circuits 15 associated with said second group of lines for controlling said electrically controlled means whereby when any connection is extended from any one of said lines of the second group to the said trunk the trunk becomes operative to extend a connection 20 therefrom, and a central battery for operating and talking purposes.

18. In a telephone system, a trunk line 25 normally inoperative whereby when a certain line is connected therewith calls are prevented from passing over said trunk, another line, an auxiliary circuit associated therewith for rendering said trunk operative whereby calls may be transmitted over 30 said trunk, and electrically controlled operating means for calling and releasing automatically, said means controlled over a portion of one side of the talking circuit in 35 series with a portion of the other side.

19. In a telephone system, a group of lines,

a trunk, another group of lines, circuit closing means for extending connection to said trunk from any one of said lines, said trunk being normally inoperative for extending a circuit thereover whereby when connection 40 is extended to said trunk from said first group of lines the connection cannot be extended beyond said trunk, electrically controlled means for rendering said trunk circuit operative, auxiliary circuits associated 45 with said second group of lines for controlling said electrically controlled means whereby when any connection is extended from any one of said lines of the second group to the said trunk the trunk becomes operative to extend a connection therefrom, and electrically controlled means for calling and releasing, said means controlled over a portion 50 of one side of the talking circuit in series with a portion of the other side. 55

20. In a telephone system, a trunk line normally inoperative whereby when a certain line is connected therewith calls are prevented from passing over said trunk, another line, an auxiliary circuit associated 60 therewith for rendering said trunk operative whereby calls may be transmitted over said trunk, and a central battery for supplying current for talking and operating purposes.

Signed by me at Chicago, Cook county, 65 Illinois, this 3 day of June, 1909.

BERNARD D. WILLIS.
